ANTENNA

Clarence W. Hansell, Port Jefferson, and Nils E. Lindenblad, Rocky Point, N. Y., assignors to Radio Corporation of America, a corporation of Delaware

Application February 3, 1936, Serial No. 62,017

15 Claims. (Cl. 250—33)

This invention relates to antennas.

A primary object is to enable the transmission of short radio waves with considerable vertical directivity and with uniform and maximum 5 radiation in the horizontal plane.

A further object is to provide an antenna suitable for use on ultra high frequencies which has a broad frequency response curve whereby it will radiate the modulation sidebands of television, 10 facsimile and other program services.

Another object is to provide a mechanically simple antenna structure of pleasing appearance suitable for use on the tops of high buildings and towers.

15 A further object is to provide a simple mechanical antenna arrangement for use with ultra high frequencies which gives the equivalent of a series of dipoles energized in the same phase with respect to one another.

20 These and other objects of the invention which may appear from a reading of the specification are achieved by providing an antenna in the form of a tube having alternately arranged radiating sections each a half wave long at the operating frequency and energized such that the currents flowing therein are in the same direction, whereby cophasal energization is effected. The radiation from an intermediate section is suppressed by means of a sleeve also a half wave length 25 long surrounding the intermediate section. The sleeve may be either insulatingly positioned with respect to or fastened metallically at its mid-point to the antenna tube and is connected to ground by means of a lead a multiple of a half 30 wave long extending within the tube from ground to the end of the sleeve nearest the high frequency apparatus.

35 The diameter of the antenna tube is selected to give a desired width of frequency response 40 curve and is based upon an appreciation of the fact that the width of the curve is increased simultaneously with an increase in diameter of the tube.

45 A feature of the invention is the adjustable sleeve at the extreme end of the antenna tube for obtaining proper adjustment of the length of the antenna.

50 Advantages of the invention are that the antenna (1) possesses moderately great vertical directivity but no horizontal directivity when erected vertically; (2) is simple to construct; (3) is rigid in construction; and (4) is easily adapted for use on the top of a high building.

55 In the accompanying drawing, Figs. 1 and 2 illustrate the invention as applied to two different lengths of antennas mounted vertically on the top of a building. It will be appreciated, of course, that the antenna may also be positioned horizontally or at any desired angle for obtain-

ing directivity in planes other than the vertical plane.

The antenna of Fig. 1 comprises, essentially, a single rod 1 equal to seven-quarters the length of the communication wave, set one-quarter of 5 a wavelength more or less into the top of a building. The portion of the antenna above the roof top consists of two half wavelength radiating portions 2, 2 separated by an effective non-radiating portion 3 from which radiation is suppressed by a surrounding sleeve 4 also equal to a half wave-length. Sleeve 4 is grounded to the roof top by a half wavelength connection 14 which connects with the sleeve at its lower end and extends inside the tubular antenna, as 10 shown. Connection 14 may connect to the inside or outside of sleeve 4. The lowest quarter wavelength section is prevented from radiating by having it sunk into the roof of the building. The antenna is energized by high frequency apparatus, shown conventionally in box form, through transmission line TL which connects with antenna 1 at a tapping point which is adjustable to match the impedance of the line TL. In this manner standing waves are set up along the 15 antenna, and the voltage which is effective in producing radiation is as indicated in dotted lines on the sections 2, 2.

20 Sleeve 4 may be insulatingly positioned, or can be fastened metallically at its mid-point to the 30 antenna tube 2. If desired, sleeve 4 may be grounded at its upper end, in which case connection 14 should be an even multiple of half the length of the operating wave.

25 An adjustable sleeve 5 aids in adjusting the 35 length of antenna 1. In order to broaden the frequency response curve of the antenna so that it may radiate the modulation sidebands, its diameter is made quite large, herein shown as one-fifteenth the wavelength.

30 The system of Fig. 2 is similar to that of Fig. 1 except that the antenna is of greater length. In Fig. 2 there are shown three radiating sections, each one-half wave-length separated from one another by half wavelength non-radiating sections in the same manner as shown in Fig. 1. In this case the uppermost sleeve 4' is grounded to the roof top by a conductor equal to three half wavelengths. Instead of such a grounding arrangement for sleeve 4', the lower end of the 45 upper sleeve 4' can be connected to the upper end of the lower sleeve 4. It will thus be apparent that if the antenna is lengthened, each sleeve may be connected to ground over a connection equal to an odd multiple of a half wavelength. Fig. 2 also differs from Fig. 1 by showing another way of coupling the transmission line to the antenna; instead of the direct coupling of Fig. 1, inductive coupling is used, both types of coupling being, of course, interchangeable.

It will be understood, of course, that the invention is not limited to the precise arrangement shown in the figures, since various modifications may be made without departing from the spirit and scope thereof. For example, the antennas of Figs. 1 and 2 may be extended symmetrically from a center so as to form a structure equivalent to two antennas end to end, somewhat like an extended dipole antenna. Also, various arrays of antennas may be used to obtain additional directivity. It should also be understood that the expression "sleeve" is not necessarily limited to a continuous, solid element but also includes a plurality of closely spaced, interconnected wires in the form of a screen and having the general configuration of a cylinder.

What is claimed is:

1. An antenna comprising two half wavelength radiating sections separated by another half wavelength section, and a sleeve one-half wavelength long surrounding said last section for preventing radiation therefrom, the ends of said sleeve on both sides of its center being insulated from said last section, and a connection grounding said sleeve.

2. An antenna comprising a straight rod having high frequency apparatus connected to one end thereof, alternate half wave sections of which, as measured from the free end, radiate, means for preventing radiation from each half wave section located between radiating sections comprising a sleeve surrounding said section, the ends of said sleeve being insulatingly positioned from said antenna, and a connection for grounding said sleeve.

3. An antenna in accordance with claim 2, characterized in this that said antenna is a tube and said connection grounding said sleeve runs inside said tube.

4. An antenna in accordance with claim 2, characterized in this that said antenna is a tube and said connection grounding said sleeve runs inside said tube, and is an odd multiple of half the length of the operating wave.

5. An antenna comprising two half wavelength radiating sections separated by another half wavelength section, and a sleeve one-half wavelength long surrounding said last section and supported therefrom only at its mid-point for preventing radiation therefrom, and a connection an odd multiple of a half wavelength long grounding said sleeve.

6. An antenna for obtaining moderately great vertical directivity and little or no horizontal directivity, comprising a vertical rod, high frequency apparatus connected to the lower end of said rod, an adjustable sleeve at the extreme top end of said rod for adjusting the length thereof, a sleeve surrounding each alternate half wavelength section of said rod and insulated therefrom, and a connection an odd multiple of a half wave long connecting each of said last sleeves and ground for preventing radiation from the surrounded sections.

7. An antenna in accordance with claim 6, characterized in this that said rod is a tube whose outer diameter is an appreciable fraction of a half wave long, and said connections extend within said tube from said sleeves to ground.

8. An antenna in accordance with claim 6, characterized in this that said antenna is mounted on the top of a building, the lowermost portion of said antenna being set below the roof top for approximately one-quarter wavelength, said

portion of the antenna above said roof top being a multiple of a half wave, said roof being of high conductivity and maintained at zero radio frequency potential.

9. An antenna in accordance with claim 6, characterized in this that said antenna is mounted on the top of a building, the lowermost portion of said antenna being set below the roof top for approximately one-quarter wavelength, said portion of the antenna above said roof top being a multiple of a half wave, said high frequency apparatus being coupled to said antenna at the portion below said roof top, said roof top being of high conductivity and grounded.

10. An antenna comprising two half wavelength radiating sections separated by another half wavelength section, a sleeve one-half wave length long surrounding said last section and insulated therefrom for preventing radiation therefrom, and a connection grounding said sleeve.

11. An antenna for obtaining moderately great vertical directivity and little or no horizontal directivity, comprising a vertical rod, high frequency apparatus connected to the lower end of said rod, a sleeve surrounding each alternate half wavelength section of said rod, the portions of said sleeve on both sides of the center being insulated from the rod, and a connection a multiple of a half wave long connecting each of said sleeves to ground for preventing radiation from the surrounding sections.

12. An antenna comprising a substantially straight hollow rod, alternate half wave sections of which radiate, means for preventing radiation from each half wave section located between radiating sections comprising a sleeve surrounding said section, and a connection inside said rod grounding said sleeve.

13. An antenna comprising a substantially straight hollow rod, alternate half wave sections of which radiate, means for preventing radiation from each half wave section located between radiating sections comprising a sleeve surrounding said section, and a connection inside said rod and insulatingly positioned with respect thereto for grounding said sleeve, said connection extending to said sleeve through an aperture in said rod.

14. An antenna comprising a substantially straight hollow rod, alternate half wave sections of which radiate, means for preventing radiation from each half wave section located between radiating sections comprising a sleeve surrounding said section, and a connection inside said rod grounding said sleeve, said connection being a multiple of half the length of the operating wave.

15. An antenna comprising a substantially vertical hollow rod, alternate half wave sections of which radiate, said rod being mounted on a grounded support and being set below the upper surface of said support for a distance approximately one-quarter the length of the operating wave, said portion above said support being a multiple of half the operating wave, means for preventing radiation from each half wave section of said rod located between radiating sections comprising a shield surrounding said section, a connection inside said rod grounding said shield, and high frequency apparatus coupled to said rod at the portion below the upper surface of said support.
